UNITED STATES PATENT OFFICE.

ELMER C. BLASDELL, OF KANSAS CITY, MISSOURI.

CRACKING APPARATUS.

Application filed May 20, 1924. Serial No. 714,636.

To all whom it may concern:

Be it known that I, ELMER C. BLASDELL, a citizen of the United States, residing at Kansas City, in the county of Jackson and State of Missouri, have invented a new and useful Cracking Apparatus, of which the following is a specification.

This invention relates to an apparatus designed for distilling or cracking hydrocarbons such as petroleum distillates or the like under either atmospheric or high pressure to recover highly volatile solvents.

The important object of the invention is to provide an apparatus including a plurality of units embodying towers, which towers and units are arranged with such communication with each other that one or more of the towers or units may be disconnected from the system, at the will of the operator for cleaning or repairing, the remaining towers or sections being sufficient to carry on the cracking process, while the towers or sections are being reconditioned.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a diagrammatical plan view of an apparatus constructed in accordance with the invention.

Figure 2 is a diagrammatical view of one of the sections in side elevation.

Figure 3 is an enlarged side elevational view of one of the sections disclosing one of the towers of the sections in longitudinal section.

Figure 4 is a sectional view taken on line 4-4 of Figure 3.

Figure 5 is a plan view of one of the sections.

Referring to the drawings in detail, the reference character 5 indicates a still which is of the usual and well known construction, the still being fed with crude oil through the pipe 6, which has communication with a suitable source of oil supply not shown.

A gate valve 7 is disposed in the pipe line 6 and provides means whereby the passage of oil through pipe 6 may be controlled,

should it be desired to cut off this unit and supply oil to the adjacent still of the next succeeding unit.

Each unit of the apparatus includes a plurality of towers indicated generally by the reference character 8 and while I have shown three of such towers in each unit, it is to be understood that the number of towers may be varied to meet various requirements.

A horizontal partitioning member 9 is disposed in each tower and as shown, the partitioning member is formed with a plurality of openings to permit vapors to pass upwardly into the upper portion of the tower where they are condensed, the condensates falling back into the lower portion of the tower while the vapors pass upwardly and out through the pipe 10 communicating therewith to the condenser box 11, associated therewith.

As clearly shown by Figure 5 of the drawings, each tower of a unit is supplied with a discharge pipe indicated at 10 for directing the vapors to the condenser box associated therewith, providing various grades of oil.

Depending from the partitioning member 9 of each tower is a baffle plate 13 which has its lower edge disposed in spaced relation with the bottom of the tower in which the same is positioned so that liquid passing into one side of the tower will be directed downwardly around the baffle 13 and into the pipe 14 which is shown as having an elbow 15 extending downwardly into the tower. It might be further stated that the oil entering the towers, fills the bottom portion thereof until the levels in the towers are in planes with the lower edges of the pipes 14 leaving the mouths of the elbows 15 submerged, providing a seal, to prevent the unrestricted passage of vapors through the towers, but at the same time allow a portion of the oil and vapors to pass to the next tower of the unit.

The feed pipe to the first tower of unit A is indicated at 16 and includes a relatively short pipe 17 that enters the lower portion of the tower as illustrated by Figure 3 of the drawings, there being provided a valve 18 for controlling the passage of oil and vapor to the tower.

The various towers of the units are connected by pipes 19 and 20 so that as oil fills the lower portion of one tower, it will pass onto the next tower through the pipe

communicating therewith. A lateral pipe 21 communicates with pipe 16 and is supplied with a valve 22 for controlling the passage of oil through the pipe 21. Branch 5 pipes 23 and 24 establish communication between the pipe 21 and pipes 19 and 20, there being provided gate valves 25 and 26 for controlling the passage of oil through these pipes. A gate valve 27 is also provided 10 in the pipe 21 and disposed between the pipes 23 and 24 to control the passage of fluid between the pipes 23 and 24.

A valve member 18 controls communication between the pipe 17 and the first tower 15 8 of the unit, and a valve member 29 controls the passage of oil and vapor from the tower 8. The reference character 30 indicates a valve member that controls the passage of oil and vapor into the second tower 20 of the unit and the reference character 31 designates a valve member for controlling the passage of oil from the second tower of the unit.

The valve 32 is disposed adjacent to the 25 third tower of the unit and is designed to control the passage of oil to the tower associated therewith, while the valve member 33 which is disposed along the opposite side of the tower controls the passage of oil 30 from the tower.

At one end of the pipe 21 is a valve member 34 for controlling the passage of oil through the pipe 21 and allowing oil to be directed to the pipe 35 leading to the next 35 section of the system, directly from the still, should it be desired to cut out the towers of the first unit of the system, to repair or clean the same. Should it be desired to cut out the entire first section of the system, 40 a feed pipe 36 is provided which communicates with the feed pipe 6 by means of the T-couplings 37, there being provided a valve 38 for controlling the passage of fluid through this pipe 36.

The pipe 35 communicates with pipe 39 through the pipe 40 and as shown, the pipe 39 is in communication with pipe 41 which constitutes the feed pipe for the towers of the next succeeding unit of the system and 50 affords means whereby the crude oil may be supplied to the towers of the succeeding unit of the system should it be desired to throw the towers of the first unit of the system out of operation.

A pump 42 is in communication with pipe 55 40 through the union 43 and communicates with the adjacent still through pipe 44, there being provided a gate valve 45 for controlling the passage of fluid to the pump, 60 while the valve 46 controls the passage of fluid from the pump 42.

If it is desired to pass fluid from pipe 40 around the pump, the valve 45 may be closed, whereupon the fluid may 65 enter pipe 47, the valve member 48 which

is disposed in the pipe line 47 may be opened, and the valve member 46 closed. It will thus be obvious that the fluid will have a free passageway to the pipe 49 which 70 communicates with the adjacent still of the succeeding unit.

Pressure valves 51' are arranged at the upper ends of the towers and may be set to regulate the pressures within the towers at 75 which the vapors may pass off.

The valve member 50 is positioned in the pipe line 39 and when the fluid is passed through pipe 47, it is obvious that this valve member 50 is also closed. In order that the towers may be cooled, a collar 51 is supported on the upper end of each tower, the collars of the towers being provided with cut out portions providing passageways to allow water fed to the collars to pass outwardly therefrom and trickle over the external surfaces of the towers slightly reducing the temperatures thereof. It might be further stated that the condenser boxes are of the usual and well known construction, and include coils 52 which are submerged in water, 90 the coils being in communication with a suitable storage tower not shown to receive the products of distillation.

In the use of the apparatus, the oil enters the system through the pipe 6 whence it passes to the still 5 associated therewith, the oil and vapors passing through the pipe 16 where they enter the first tower of the first unit of the system. The vapors now pass upwardly through the tower the condensates falling to the bottom thereof. It will be obvious that as the liquid and vapors enter the tower, the temperature thereof is slightly reduced and the oil and vapors that are not carried out through the first towers enter 100 the second tower of the unit at a slightly less degree of temperature, but said second tower is maintained at a higher temperature than is the first tower, causing a vaporization of 105 a fraction of the oil.

The vapors from the liquid in this tank pass upwardly through the tower and enter the pipe 10 communicating therewith through the upper end thereof, whence the vapors are carried off to suitable condensing blocks.

The unvaporized oil and condensates collect at the bottom of the second tower of the unit, and pass into the third tower of the section at a slightly reduced temperature, the vapors passing upwardly through this tower where they are carried off through the pipe 10 associated therewith to suitable condensing box. The liquid now is passed to the second unit of the system, and enters the still associated therewith from where the vapors and liquid pass into the first tower of this unit and the process of distillation described is repeated.

Should it be found necessary to discon- 120

nect for example, unit A, valve 7 and valves 18 and 22 are closed and the valve 38 opened, allowing the crude oil to pass through pipe 36. Valve members 33 and 34 are now closed to direct the crude oil through pipes 35, 40 and through the pump 42 from where the oil is directed to the still of the unit B. It is to be understood that valve members 48 and 50 are closed, and the valve members 45 and 46 opened to permit the oil to pass through the system in this manner.

If it becomes necessary to disconnect tower number 1 of the first unit to clean or repair the same, the valve members 18 and 29 may be closed and the valve members 22 and 25 may be opened. Thus it will be seen that the fluid will now pass from the still of the first unit directly to the second tower of unit A through the pipes 16, 19 and past valve member 30.

Due to the arrangement of pipes, towers and gate valve, it will be obvious that any one of the towers of a unit, or any unit of the system may be readily disconnected for the purpose of repair or cleaning and the system maintained in operation continuously, thereby eliminating the necessity of shutting down the system in order to prepare any portion of the apparatus.

30 I claim:—

1. In an apparatus for cracking oil, a plurality of towers connected in series, valved connections between said towers whereby

one or more of said towers may be cut out of the system, a chamber in the lower portion of each tower, a baffle suspended in said chamber, a pipe leading from the upper portion of each chamber and located above the lower end of the baffle for conducting fluid to the succeeding tower, means for externally cooling said towers whereby certain fractions may be condensed, and means in the top of each tower for withdrawing the uncondensed vapors.

2. In an apparatus for cracking oil, a plurality of towers connected in series, valved connections between said towers whereby one or more of said towers may be cut out of the system, a chamber in the lower portion of each tower, a baffle suspended in said chamber, a pipe leading from the upper portion of each chamber and located above the lower end of the baffle for conducting fluid to the succeeding tower, means on the tops of the towers for externally cooling said towers whereby certain fractions may be condensed, and means in the top of each tower for withdrawing the uncondensed vapors.

In testimony that I claim the foregoing as my own, I have hereto affixed my signature in the presence of a witness.

ELMER C. BLASDELL.
